COMBINATION ELECTRIC METER AND PUSHBUTTON PANEL

Andrew T. Kostanecki, New Canaan, Conn., assignor to
General Electric Company, a corporation of New York

Filed Nov. 2, 1961, Ser. No. 67,352

Term of patent 14 years

(Cl. D26—13)

FIG. 1.

FIG. 2.

FIG. 1 is a front elevational view of a combination electric meter and pushbutton panel, showing my new design; and

FIG. 2 is a fragmentary cross-sectional view taken along the line 2—2 of FIG. 1.

The dominant features of my device reside in the portions shown in solid lines.

I claim:

The ornamental design for a combination electric meter and pushbutton panel, as shown and described.
